GLASS COMPANY, OF TOLEDO, OHIO, A CORPORATION OF OHIO.

DISH.

No. 839,123.

Specification of Letters Patent.

Patented Dec. 25, 1906.

Application filed June 30, 1906. Serial No. 324,276.

To all whom it may concern:

Be it known that I, WILLIAM F. DONOVAN, a citizen of the United States of America, residing at Toledo, in the county of Lucas and State of Ohio, have invented certain new and useful Improvements in Dishes, of which the following is a specification, reference being had therein to the accompanying drawing.

The invention relates generally to a dish, preferably of pressed glass, and particularly to a dish of this character provided with compartments adapted for articles of various kinds; and the invention consists in the novel and peculiar construction of the compartment-dish, wherein the partitions or dividing-walls in addition to forming the compartments serve to strengthen the structure and give an ornamental appearance to the entire article.

The single drawing illustrating my invention is a perspective view of the dish proper.

In construction the dish consists of a bowl-shaped body A, comprising a base or bottom section B and an inclosing preferably annular wall C.

D represents a partition or wall extending in this instance diametrically across the dish and in height corresponding substantially to the depth of the dish as illustrated, the upper edge of the partition approaching approximately to the rim E.

Preferably, but not necessarily, a second or complementary partition F is used, intersecting the first-mentioned partition at right

angles and corresponding in height and lateral length to the other. Both these partitions are integral with the dish proper and serve, in addition to forming the compartments, as strengthening members reinforcing the dish.

G H represent suitable handles for the dish, connected to the dish-body at points opposite one of the partitions, as D. This construction is desirable, as the said partition forms a tie or connecting member intermediate of the handles, thus transmitting the strain that is imparted to the dish and serving to strengthen the entire structure.

What I claim as my invention is—

1. A pressed-glass dish comprising a bowl-shaped body, an integral diametrically-extending partition-wall therein, and handles joined to the body at the extremities of the dividing-wall.

2. A pressed-glass dish consisting of a bowl-shaped body having integral intersecting partition-walls extending diametrically across the body and upwardly from the bottom in proximity to the rim, and handles for the body attached to the latter at the extremities of one of the partitions.

In testimony whereof I affix my signature in presence of two witnesses.

WILLIAM F. DONOVAN.
